United States Patent Office.

ABIJAH WALLACE, OF STROUDSBURG, PENNSYLVANIA, ASSIGNOR TO
THE TANITE COMPANY, OF SAME PLACE.

Design No. 4,321, dated August 30, 1870.

DESIGN FOR THE FRAME OF AN EMERY GRINDER.

The Schedule referred to in these Letters Patent and making part of the same.

To all whom it may concern:

Be it known that I, ABIJAH WALLACE, of Stroudsburg, in the county of Monroe and State of Pennsylvania, have invented a new Design for the Frame of an Emery Grinder; and I do hereby declare that the following is a full, clear, and exact description of the same, reference being had to the accompanying drawings forming part of this specification, and in which—

Figure 1 is a front view; and

Figure 2, a back view of the frame, both in perspective.

Figure 3 is a transverse vertical section of one side of the entablature.

Figure 4 is a horizontal section of one of the legs.

Similar letters of reference indicate corresponding parts in the several figures.

The frame consists of an open entablature, A, having at its front corners forwardly projecting rest-brackets, a a, having standing up above it the two journal boxes C C, for the reception of the shaft of the grinder, and having for its support four legs, B B B B.

The plan of the entablature is oblong with its rear corners rounded. Its transverse sectional form is shown in fig. 3.

The legs B B B B are of such curved form that the two at either end combine to form one arch; the

two in front combine to form another and the two at the back combine to form another. The transverse sectional form of the legs is shown in fig. 4.

On the space over the arch of the two front legs and below the cornice e of the entablature, shown in fig. 1, are bas-relief ornaments, b b, of a leafy character, and between them a bas-relief scroll, c c.

On the corresponding space over the arch of the two rear legs, shown in fig. 2, are similar ornaments, b b, with a bas-relief representation, d, of an emery-wheel between them.

On the corresponding space over the arches at each end are bas-relief ornaments, f, the form of which is shown in figs. 1 and 2.

The form of the journal-boxes can be better understood by reference to figs. 1 and 2 than by any concise description.

What I claim as my invention, and desire to secure by Letters Patent, is—

The design and configuration of the frame of an emery grinder as herein shown and described.

ABIJAH WALLACE.
